UNITED STATES PATENT OFFICE.

DONALD F. WHITING, OF NEW YORK, N. Y., ASSIGNOR TO WESTERN ELECTRIC COMPANY, INCORPORATED, OF NEW YORK, N. Y., A CORPORATION OF NEW YORK.

MOUNTING AND PROTECTING ELECTRICAL APPARATUS.

Application filed June 1, 1920. Serial No. 385,439.

To all whom it may concern:

Be it known that I, DONALD F. WHITING, a citizen of the United States, residing at New York, in the county of Bronx, State 5 of New York, have invented certain new and useful Improvements in Mounting and Protecting Electrical Apparatus, of which the following is a full, clear, concise, and exact description.

10 This invention relates to electrical systems and has particular reference to the mounting of telephone repeater equipment on panel boards or racks.

One object of the invention is to most efficiently reduce the cross-talk which may 15 occur between adjacent pieces of apparatus.

Another object is to substantially eliminate the possibility that such apparatus as vacuum tubes, used in repeaters, shall 20 become overheated due to inefficient dissipation of the heat generated by them during their operation.

The invention in general comprises, in the first place, the interposition between pieces 25 of apparatus between which cross-talk is likely to occur, of other pieces of apparatus used on the panels, which have metallic casings which are grounded and act as magnetic shields. On such racks it has been 30 found that the input and output transformers, the various batteries and potentiometers can thus be used. Since these pieces of apparatus are already in use on racks of this type, the practice of the invention does not 35 require any additional apparatus.

Furthermore, it has been found that the vacuum tubes become overheated when their space relations with respect to the other apparatus on the racks are not proper. This 40 invention therefore further involves the assembly of the apparatus on the racks so that open spaces as large as possible shall be provided around the vacuum tubes and that the general disposition of the tubes on the 45 racks shall be such as will form vertical flues or channels up which the air heated by the tubes may pass without obstruction.

Furthermore, the invention involves the assembly, close together, of those pieces of 50 apparatus of higher impedance so that they shall have little or no effect on the other parts.

Further objects of the invention will be made apparent in the following detailed description taken in connection with the ac- 55

companying drawing, in which Fig. 1 is a schematic representation of a panel board having a plurality of racks thereon; Fig. 2 is a horizontal cross-section taken through part of the apparatus as indicated by line 60 2-2 in Fig. 1 and shows the way in which the apparatus is grouped to form air flues; and Figure 3 is a diagram of a circuit, such as a two-wire repeater circuit, in which the parts of especially high impedance are de- 65 noted in heavy black lines.

As shown in Fig. 1, the panel board comprises a plurality of vertical bars 5, to which are suitably fastened tiers of racks 6. Each rack is provided with a complete set of repeater apparatus which may be used in two or four wire circuits. In view of the necessity of using large numbers of these racks, they must be placed as close together as possible in the interest of economical spacing, 70 75 and therefore it has been found that unless special provision is made, cross-talk will occur between apparatus on one rack and that on others either vertically or horizontally adjacent thereto. In referring to a piece of apparatus on the racks in Fig. 1 by number, the corresponding part of the circuit in Fig. 2 will be denoted with the same number so that the circuit relation of the apparatus shown on a rack in Fig. 1 may 80 85 be readily ascertained from Fig. 2.

Considering the middle rack shown in Fig. 1, and noting the apparatus on this rack from left to right, there is a potentiometer 7, a relay 8, an input transformer 9 and condensers 10, 11 and 11'. Next in order are a vacuum tube 12, a resistance potentiometer 13 and its mounting plate 13', and another vacuum tube 14, to the right of which are batteries 15 and 16. 90 95

It will be noted that in Fig. 3, the connecting wires between input transformer 9 and the grid of the vacuum tube 12, the connecting wires between the plate of vacuum tube 12 and the potentiometer 13, and the connecting wire between the potentiometer 13 and the grid of vacuum tube 14, are shown in heavy black lines. This is to indicate that these wires and the parts to which they are connected are of high impedance with respect to ground. If these wires are placed closely adjacent to portions of other circuits to which cross-talk might be transmitted, such an action is likely to take place. Therefore, it becomes necessary that 100 105 110

these parts and their connections be disposed as close together and as far removed from susceptible portions of other racks as possible.

5 It sometimes happens that cross-talk may occur between tube 12 and the potentiometer 7 on the racks immediately above, below, or to either side of any particular tube 12. To eliminate the possibility of this action, it will 10 be noted that between tube 12 and the potentiometer 7 on the rack above or below, there are disposed the metallic casings of condensers 10, 11 and 11' and transformer 9, all of which casings are grounded. This arrangement of apparatus has been found by 15 many and exhaustive tests to substantially eliminate cross-talk between the above mentioned two pieces of apparatus. It has also been found that cross-talk may occur between tube 12 on one rack and 14 on another. In order that this defect may be eliminated, it will be noted that on any two adjacent racks between the tube 12 and the tube 14, there is schematically represented the 20 grounded end of the potentiometer 13 which in this instance acts effectually as a shield.

Furthermore, it has been found that cross-talk occurs between tube 14 and potentiometer 7 on adjacent racks. Accordingly, 30 this defect is eliminated by the interposition of the casings of batteries 15 and 16 between the tube 14 and potentiometer 7. These casings being grounded, they form an effectual shield between the parts mentioned. Furthermore, it will be noted that 35 the transformer 9, vacuum tubes 12 and 14, and the upper end of the potentiometer 13, which are of high impedance, are located adjacent to portions of the rack immediately above them on which grounded apparatus is located and which therefore is of 40 zero potential.

It will furthermore be noted that the various vacuum tubes on the racks are arranged 45 in such a vertical relation that fairly open spaces are provided around each tube and corresponding tubes of each rack are arranged in vertical series so that the heat generated by the tubes tends to pass upwardly along this channel or flue. The formation of these flues is further aided by the depth dimensions of the transformers 9, the potentiometer 13, and the battery boxes 15 as clearly shown by the cross-section in Fig. 50 2. It has been found that the tendency to overheat on the part of the vacuum tubes is therefore very efficiently reduced.

A circuit arrangement of the same general type as the one shown in Fig. 2 is described 60 in my Patent No. 1,378,392, May 17, 1921, signaling systems.

What is claimed is:

1. Amplifying means, said means comprising a vertical row of amplifying tubes 65 and circuit apparatus auxiliary thereto, said

circuit apparatus being so arranged laterally of and adjacent to said tubes that a vertical passage-way is provided for the air heated during the operation of said tubes.

70

2. In combination a telephone repeater panel board, vacuum tubes and other electrical apparatus mounted on said panel board, the majority of said apparatus projecting from said board a distance substantially at least as far as said tubes, said apparatus being so arranged with respect to said tubes that vertical flues are provided for the air heated during the operation of said tubes.

75

3. A telephone repeater panel board comprising a plurality of repeater racks, apparatus on each rack of high impedance with respect to ground, and a plurality of grounded magnetic shields between this apparatus on adjacent racks.

80

4. A telephone repeater panel board comprising a plurality of repeater racks, apparatus on each rack adapted to affect apparatus on other racks to produce cross-talk, and a grounded shield between said apparatus on adjacent racks.

85

5. A telephone repeater panel board comprising a plurality of repeater racks, apparatus on each rack of high impedance to ground, said racks being so disposed that said high impedance apparatus is adjacent a piece of apparatus of substantially zero potential to ground on an adjacent rack.

90

6. A telephone repeater panel board comprising a plurality of repeater racks, apparatus of high impedance to ground on each rack, said apparatus being substantially surrounded by grounded apparatus to prevent cross-talk between racks.

100

7. A telephone repeater panel board comprising a plurality of repeater racks, devices mounted on each of said racks, said devices on each rack comprising a thermionic discharge tube, a potentiometer and condensers having grounded metallic casings, certain of said condensers being so interposed between a device on one rack and a potentiometer on an adjacent rack as to prevent cross-talk therebetween.

110

8. A telephone repeater panel board comprising a plurality of repeater racks, devices mounted on each of said racks, said devices on each rack comprising a thermionic discharge tube, a potentiometer and batteries having grounded metallic casings, certain of said batteries being so interposed between a device on one rack and a potentiometer on an adjacent rack as to prevent cross-talk therebetween.

120

9. A telephone repeater panel board comprising a plurality of repeater racks, devices mounted on each of said racks, said devices on each rack comprising a transformer having a grounded metallic casing, an electron 130

125

discharge tube, and a potentiometer, certain of said transformers being so interposed between a device on one rack and a potentiometer on an adjacent rack as to 5 prevent cross-talk therebetween.

10. A panel board comprising racks, devices comprising thermionic discharge tubes and circuit apparatus auxiliary thereto mounted on each of said racks, certain of 10 said devices on one rack tending to affect certain of said devices on another rack to produce cross talk, and a grounded shielding means between said certain devices on said one rack and said certain devices on 15 said other rack.

11. A panel board comprising racks, devices comprising thermionic discharge tubes and circuit apparatus auxiliary thereto mounted on each of said racks, certain of

said devices on each rack being of high 20 impedance to ground, said devices and racks being so disposed that said certain devices on one rack are adjacent devices of substantially zero potential to ground on an adjacent rack.

25 12. A panel board comprising racks, devices mounted on each of said racks, said devices on each rack comprising thermionic discharge tubes and circuit apparatus auxiliary thereto, certain of said devices on each rack being grounded, and others of said devices on each rack having high impedance to ground and being substantially surrounded by said grounded devices.

In witness whereof, I do hereunto subscribe my name this 27 day of May A. D., 1920.

DONALD F. WHITING.
